UNITED STATES PATENT OFFICE.

ANDERS CONRAD HANSON, OF RED OAK, IOWA.

WIRE-STRETCHER.

1,156,597.

Specification of Letters Patent.

Patented Oct. 12, 1915.

Application filed June 17, 1914. Serial No. 845,563.

To all whom it may concern:

Be it known that I, ANDERS CONRAD HANSON, a citizen of Sweden, residing at Red Oak, in the county of Montgomery and 5 State of Iowa, have invented certain new and useful Improvements in Wire-Stretchers, of which the following is a specification.

My invention relates to improvements in 10 tools for stretching wire and more particularly to a tool adapted primarily for stretching screen wire to enable the same to be properly fitted into the screen frame.

With the foregoing and other objects in 15 view the invention consists in the combination and arrangement of parts to be hereinafter fully described in the following specification, pointed out in the claims and illustrated in the accompanying drawing 20 which forms a part of said specification and in which—

Figure 1 is a side elevation of my improved wire stretcher in use. Fig. 2 is a 25 top plan of the same taken on line 2—2 of Fig. 1. Fig. 3 is a cross section through the handle and is taken on line 3—3 of Fig. 1. Fig. 4 is a cross section taken on line 4—4 of Fig. 1. Fig. 5 is a section taken on line 5—5 of Fig. 1.

Like reference characters indicate corresponding parts throughout the several views.

My tool comprises the upper and lower levers 1 and 2 which are pivoted together at 3 and formed forward of the pivot with 35 the gripping jaws 4, 5. A spring 6 secured to lever 2 tends to force the jaws apart. To the lever 1 the handle is secured which comprises the casing 7 which is fixed with relation to said lever, and the tube 8 disposed 40 upon the casing and encompassing and sliding upon the same and which tube is provided with the set screw 9 by means of which it may be releasably locked in engagement with said casing.

To the casing 7, near its lower end, the 45 integral ears 10 of a two piece lever 11 are pivoted as at 12 and said lever pivotally carries a gripping block 13 between its lower extremities as at 14, which block is 50 formed with teeth or serrations as at 15 and, moreover, is engaged by a pin 16 projected through the arcuate slot 17 formed in one portion of the two-piece lever 11, said pin, further, being engaged by a spring 55 18 that is secured to a pin 19 secured upon the slotted lever portion 11, the purpose of

the spring and pins just described being to tilt the gripping block forward upon its pivot or into engagement with the work. The lever 11, rearwardly of the ears 10, 60 is formed with a projection 19 disposed partly beneath the casing 7 for engagement with a thumb screw 20 secured by a strap 21 to that casing, and a spring 22 also secured to the casing 7 at its free termination 65 frictionally engages the lever 11.

Operation: 23 designates the frame and 70 24 the screen wire to be fitted thereto. The wire 24 is fastened to the opposite side (not shown) of the frame 23 and the adjacent end of the screen wire is grasped between the jaws 4, 5 of the tool. The gripping block 13 is placed in engagement with the frame and the thumb screw 20 screwed down until said block obtains a firm purchase upon the frame. By pressing down upon the tube portion 8 of the handle, the ears 10 of lever 11 serve as a fulcrum for the casing 7 and the jaws 4, 5 stretch the wire 24 with relation to the screen 23. 80 Greater leverage may be obtained by extending the tube 8 upon the casing 7.

What is claimed is:—

1. In a wire stretcher, a pair of levers pivoted together and terminating in jaws, 85 a telescoping handle carried by one of said levers, a fulcrum for said handle, a gripping block pivotally carried by said fulcrum, flexible means connecting said fulcrum and gripping block whereby the latter is retained in operative position and means carried by said handle for engagement with said fulcrum whereby the same may be caused to drive said gripping block 90 into the work.

2. In a wire stretcher, a pair of levers pivoted together and terminating in jaws, a telescoping handle carried by one of said levers, a slotted fulcrum for said handle, a gripping block terminally carried by said 100 fulcrum, a spring-pressed pin disposed in the slotted portion of said fulcrum and in engagement with said gripping block and means carried by said handle for engagement with said fulcrum whereby the same may be made to drive said gripping block 105 into the work.

3. In a wire stretcher, a pair of levers pivoted together and terminating in jaws, a telescoping handle carried by one of said 110 levers, a fulcrum for said handle, a gripping block pivotally carried by said ful-

crum, means connecting said fulcrum and gripping block for retaining the latter in operative position, a spring carried by said handle frictionally engaging said fulcrum and a thumb screw carried by said handle for engagement with said fulcrum whereby the latter may be caused to drive said gripping block into the work.

In testimony that I claim the foregoing as my own I have hereto affixed my signature in the presence of two subscribing witnesses.

ANDERS CONRAD HANSON.
